UNITED STATES PATENT OFFICE.

ABRAHAM ROCKSTAD, OF LADYSMITH, WISCONSIN.

SLEIGH KNEE.

1,413,542.

Specification of Letters Patent. Patented Apr. 18, 1922.

Application filed May 17, 1921. Serial No. 470,263.

To all whom it may concern:

Be it known that I, ABRAHAM ROCKSTAD, a citizen of the United States, residing at Ladysmith, in the county of Rusk, State of Wisconsin, have invented certain new and useful Improvements in Sleigh Knees; and I do hereby declare the following to be a full, clear, and exact description of the invention, such as will enable others skilled in the art to which it appertains, to make and use the same.

This invention relates to new and useful improvements in sled or sleigh parts and particularly to sleigh knees.

One object of the invention is to provide a sleigh knee which will permit the runner to rock in the proper manner, fore and aft, while preventing the forwardly and rearwardly sliding thereof.

In the sleigh knees, as now made, there is provision for the forward and rearward rocking of the runners, but when going up hill the upper portion of the knee, which is attached to the box or body of the sleigh, will slide backwardly, while upon going down hill, this portion will slide forwardly. It is the particular object of the invention to provide a sleigh knee, formed of two parts, but wherein the parts will not be permitted this objectionable sliding movement.

Other objects and advantages will be apparent from the following description when taken in connection with the accompanying drawings.

In the drawings:

Figure 1 is a side elevation of a sleigh knee made in accordance with the invention, and in connection with the runner and bumper.

Figure 2 is an end elevation of the knee, the runner being shown in cross section.

Figure 3 is an enlarged vertical transverse central sectional view through the knee and runner, as well as the beam, on the line 3—3 of Fig. 1.

Figure 4 is a horizontal longitudinal sectional view on the line 4—4 of Figure 1, above the lugs of the lower section of the knee.

Figure 5 is a vertical transverse central sectional view taken on the line 5—5 of Fig. 1.

Referring particularly to the accompanying drawings, A represents the lower portion of the knee, as a whole, said portion comprising an elongated inverted channel

member 10 which straddles the upper edge portion of the runner shoe 11, and is secured thereto by the vertical bolts 12 passed through the ends of the portion 10 and 60 through the runner shoe. Formed on the upper face of the channel member 10, and extending vertically therefrom, at points adjacent the ends thereof, are the posts 13, connected at their upper ends by the longitudinally extending bar 14. It will be noted that the portions of this connecting bar 14, at the upper ends of the posts, are wider than the portion which extends between the posts, thereby forming the shoulders 14', 70 the purpose of which will appear later herein. On the lower end of each post, and extending inwardly, along the upper face of the channel members, toward the other post, is a lug 15, having its outer end rounded, as 75 seen in the sectional view Fig. 4.

The other portion B, of the knee, consists of a channel member 16 on the upper edge portions of the side walls of which are formed the flanges 17, which are arranged to be secured to the lower face of the bumper or beam 18. In the opposite ends of the bottom wall of the channel member 16 are formed the recesses 19, each of a size and shape to receive one of the before-mentioned 85 lugs 15.

When the portion B is assembled in connection with the portion A, the bottom wall of the portion B is disposed on the upper wall of the portion A, and between the posts 13, with the lugs 15 disposed within the recesses 19. The lengths of the flanges 17 are slightly less than the distance between the shoulders 14', at one end of the bar 14, and those at the other end, so that there will be 95 a slight play of the portion B on the portion A.

The end portions of the beam 18 are provided with series of openings 18' for the reception of the bolts 17', which secure the 100 flanges 17 to the beam. By this arrangement, the width of the sled may be varied according to the desires of the user, or the character of the work to be performed.

By reason of the fact that the upper portion B is slightly rounded this permits rocking movement of this part with respect to the other, while the other portion A is flat, thus obviating any tendency to sudden slipping or sliding from one side to the other.

What is claimed is:

A sleigh knee comprising a lower part and

an upper part, the lower part consisting of an inverted channel having vertical posts adjacent its ends, the lower portions of the posts having inwardly directed lugs, a connecting bar extending between the upper ends of the posts and having its intermediate portion reduced forming shoulders at the posts, the upper part consisting of a channel member disposed on the lower part with its side walls at opposite sides of the bar and posts, said upper part having recesses in the ends of its bottom wall receiving the lugs

of the posts, and flanges on the upper ends of its sides disposed in the plane of the connecting bar and between the shoulders at one post and the shoulders at the other post, and a removable bolt disposed through the side walls and beneath the connecting bar. 15

In testimony whereof, I affix my signature, in the presence of two witnesses.

ABRAHAM ROCKSTAD.
